REFINING VESSEL DRAW-OFF SYSTEM

Alton L. Sawyer, Morristown, N. J.

Application February 19, 1951, Serial No. 211,685

1 Claim. (Cl. 210—51)

1

This invention deals with the increasing of yields in the refining of fatty oils by use of a multi-tube draw-off system. More specifically, it relates to a liquid phase indicating system for the drawing off of layers after multi-layer settling in the refining of fatty oils.

During the refining of fatty oils such as cottonseed oil, soy bean oil, and the like, the oil is run into a vertical tank and the reagents such as caustic soda and water are fed into the top. The mixture is then agitated for a certain length of time under specified temperature and pressure conditions, and allowed to settle. In the settling operation, the heavier aqueous soap stock falls to the bottom of the tank as a separate layer. There is generally an emulsion layer floating on this soap stock layer, composed of particles of refined oil and soap stock. Disposed above the emulsion layer is the refined oil layer.

In conventional drawing-off operations, it is necessary to draw off the soap stock layer and the emulsion layer. If some of the emulsion is left behind, it reduces the quality of the refined oil. However, if the emulsion layer is drawn off completely and some oil layer is also drawn off, the yield of refined oil is obviously reduced. In conventional practice, the tendency is to maintain good refined oil quality and, to insure complete removal of the emulsion layer, some of the refined oil layer is also drawn off and wasted.

Attempts have been made to reduce this wastage of refined oil by use of sight glasses in the draw-off line at the bottom of the settling tank. However, such glasses usually become coated with emulsion layer, so that by the time this layer is cleared off by the flowing liquid, an appreciable loss of refined oil results. Also, even if the difference in phases is observed at the proper time, there is still loss of refined oil incurred by the time the draw-off line valve is completely closed.

An object of the present invention is to enable visual and other examination of the flowing mass within the tank to determine the downward progress of the various phases therein. Another object is to enable detection of the upper phase change of the emulsion layer in sufficient time to allow for shutting off of the draw-off line valve before any wastage of refined oil takes place. Other objects will become apparent from the description which follows. These objects are attained by inserting into the bottom of the tank two small bleed lines, one of which penetrates the liquid in the bottom of the tank while the other draws off liquid at the very bottom of the tank.

2

The invention will be more clearly understood by reference to the drawing in which Figure 1 shows a vertical cross sectional view of a portion of the settling tank, while Figure 2 is a similar view of the bottom portion of the tank showing a different arrangement for the bleed lines. Similar numerals refer to similar parts in the various figures.

Referring again to the drawing, numeral 1 represents a vertical tank having lower tapered portion 16 terminating with flanged collar 2 to which disk head 3 is bolted. Outlet or draw-off line 4 is inserted into head 3 to enable drawing off of contents in tank 1. Valve 5 is provided in draw-off line 4 for throttling and shut-off purposes. In tank 1 (Figure 1) may be observed the lower soap stock layer 8, the intermediate emulsion layer 7 and upper refined oil layer 6.

As shown in Figure 1, tube 12 is inserted through head 3 to enable drawing off the contents from the very bottom of tank 1. Also, inserted through conical portion 16 of tank 1 is line 9, the upper end 10 of which extends into the liquid in the conical portion of the tank near the center thereof. Both lines 12 and 9 are provided with shut-off valves 13 and 11 respectively. End 10 of tube 9 is disposed far enough within tank 1 to enable one, when valve 5 is completely open, emptying tank 1, to close valve 5 in sufficient time to prevent refined oil 6 from being discharged therethrough.

This control is accomplished by opening valves 11 and 13 when valve 5 is opened to discharge the contents of tank 1. As the contents are discharged through discharge line 4, small streams are simultaneously discharged through lines 9 and 12. These small streams enable the operator to sample and inspect, as well as smell and feel the material flowing past their intake points. Thus, for example, when emulsion 7 reaches inlet 10 of tube 9 in Figure 1, it will be immediately transferred through tube 9, so that the operator sampling the discharge at the outlet of tube 9 will immediately detect that the emulsion is entering the conical section of tank 1. Since end 10 is placed far enough in tank 1, the operator can then proceed to throttle valve 5 and be ready to shut off the flow completely as soon as the refined oil phase 6 begins to discharge out of bleed line 12, thereby preventing any loss of valuable refined oil.

Figure 1 shows one modification of the placement of bleed tubes 9 and 12. Another modification is depicted in Figure 2. In this case, tube 9' is installed in head 3 of the tank, while tube 12'

is mounted in the lower portion of collar 2. Although these locations in Figures 1 and 2 are preferred, there is no particular limitation as to the manner in which the tubes 9 and 12 are mounted as long as tube 9 or 9' has its upper end 10 extending into the liquid drained far enough to give the operator sufficient time to close valve 5 without losing valuable refined oil. It is also required that the tank connection of line 12 or 12' be as close to the bottom of tank 1 as possible. It is apparent from the drawing that the outlets of lines 9 and 12 may be drained off to the soap stock tank or any other suitable container.

In actual practice, draw-off line 4 is usually about 4" pipe, more or less, while lines 9 and 12 are 3/4" pipe. If the diameter of line 9 is too small, the flow therethrough may be too slow due to the high viscosity of the fluids transferred. Conversely, if the diameter is too large, it may be necessary to throttle valve 11 which would then cause a physical change to take place in the case of the emulsion due to the orifice effect which breaks the emulsion.

It is preferable to insert upper end 10 of line 9 into above about 1/4 to 1/5 of the volume of the soapstock originally present to insure a time lag during discharge sufficient to close valve 5 without discharge of refined oil. Also, end 10 of pipe 9 should be far enough away from the inner wall of tank 1 to avoid catching therein any film or other undesirable material which may be sliding down the side of the vessel. Numeral 14 represents a conventional sight glass which is normally used and which has been mentioned previously herein.

The apparatus of the present invention also allows the operator to draw out, with accuracy, only the soapstock, thus enabling him to treat the emulsion by heat or chemicals to recover additional oil, without the complicating presence of

the emulsifiable soapstock. Although soapstock is mentioned here as the bottom layer, it could also consist of wash water, clean water or the like.

I claim:

5 A process for discharging, with minimum oil loss, some of the contents from the bottom of a tank provided with a discharge valve and used in settling fatty oils which had been treated with a heavier aqueous liquid, said contents being composed of a bottom aqueous layer, a supernatant top oil layer, and a supernatant intermediate emulsion layer of oil and aqueous liquid, comprising, while discharging said contents, the step of drawing a first substantially continuous bleed sample from within the liquid disposed in the bottom of the tank until a supernatant layer is observed, then closing the discharge valve gradually, drawing a second substantially continuous bleed sample from the bottom of the tank, and 10 closing the discharge valve completely when the supernatant layer is observed in the second bleed sample, said first bleed sample being drawn from the liquid at a point separated vertically from the point of drawing of said second bleed sample by a volume equal to at least about one-fifth to one-fourth of the volume of the bottom aqueous layer originally present therein, thereby allowing sufficient time for closing the discharge valve with- 15 in the time interval when the supernatant layer 20 is first observed at the two bleed lines.

ALTON L. SAWYER.
